UNITED STATES PATENT OFFICE.

FREDERICK C. AVERY, OF CHICAGO, ILLINOIS.

GAS-ENGINE.

1,135,650.

Specification of Letters Patent. Patented Apr. 13, 1915.

Application filed November 10, 1910. Serial No. 591,729.

To all whom it may concern:

Be it known that I, FREDERICK C. AVERY, a citizen of the United States, and a resident of Chicago, Illinois, have invented a new and useful Improvement in Gas-Engines, of which the following is a specification.

My invention relates to improvements in that class of gas engines in which the cylinder is vertical but inverted, that is, the cylinder is located below the crank shaft with the combustion chamber at the lower end near the base or foundation of the engine.

The object of my invention is to add to the utility of the gas engine and to provide an engine of more simple, durable and rigid construction, also to produce an engine with the least possible labor by doing away with much of the expensive machine work and I attain this result with a form of construction that will allow many of the usual component parts to be cast in one aggregate whole.

Referring to the accompanying drawings; Figure 1. is a front view of the base, column and top portion of the engine. Fig. 2. is a side view of same. Fig. 3. is a vertical section indicated by dotted lines in Fig. 2. showing the cylinder in position. Fig. 4. is a vertical section of same indicated by dotted lines in Fig. 1. Fig. 5. is a top view with the cover and cap parts removed, showing the crank and cam shaft in place. Fig. 6. is a cross section indicated by dotted lines in Fig. 2. showing the cylinder and its relation to the exhaust and inlet ports. Fig. 7. is a vertical section as indicated by dotted lines in Fig. 2. showing the valve and cam shaft in place. Fig. 8. is a top view of the cover and lid. Fig. 9. is a broken vertical section showing the method of fastening a sleeve inside of the cylinder portion.

Referring to Figs. 3. and 4. A. is the base portion, B. the column portion which are cast together, a cylinder portion V. is shown connected with the base portion A. by the wall surrounding the hole P. which leads to the combustion chamber of the cylinder V. The cylinder V. is also connected with the column B. by the wall n. Connecting with and cast to the cylinder V. and the column B. is the inlet chest F. and the exhaust chest E. which is shown in Fig. 6. a crank shaft bearing X. and a cam shaft bearing Y. is also a part of the column B. shown in Figs. 5. and 8.

Surrounding the cylinder V. and inside of the column wall B. is a water space S. It will be noticed that this water space S. also surrounds the exhaust port H. and the ignition opening K. as shown in Figs. 6. and 7. and extend under the cylinder V. shown as S. in Figs. 3. and 4. The top portion of the column B. together with the wall portion n. and the curved wall t. form the lower half of a housing for the governor h. the cams e. e. and the gears d. d. The inlet chest F. and the exhaust chest E. communicate with the cylinder V. by a passage T. and are divided from each other by the wall W.

H. is the outlet leading from the exhaust chest E. and G. is the inlet leading to the inlet chest F. each of which is a part of the casting forming the base A. and the column B.

In Fig. 7. I have shown the inlet valve b. fitted to a common type of valve cage g. while the exhaust valve a. is fitted to the casting. It is plain that either of the two valves may be used with or without a cage. In the larger types of gas engines a cage 80 would be used while in small engines that can be turned upside down without trouble no cage would be needed as the valve could be removed through the hole Z. which would after be covered with the usual pipe plug. 85 If cages are used they will be held in place by the clamp M.

The holes Q. Q. are cored to support the large cores for the water space S. when molding in the foundry, and are afterward 90 plugged. The hole P. is used in molding for a core support for the cylinder core, it is also used to support a cutter when the cylinder is bored, but when the engine is finished this hole is also permanently 95 plugged.

It will be noticed that the base A. and the column B. are of a rectangular shape, the column B. extending forward far enough to inclose the exhaust chest E. and the inlet chest F. leaving a space R. through which the valve stems a—b connect with the cams e. e. on the cam shaft N. The rear of the column B. also extends beyond the curved wall t. far enough to provide for an opening U. at the top through which water is poured into the chamber S. in order to keep the engine cool; this top U. also provides for expansion in case the water is frozen in chamber S.

100

105

110

The form of the column B, as described together with its base portion A, extending beyond its sides greatly adds to the rigidity of the engine. This shape as shown and described brings the cylinder in a central position, providing a good extending foundation to support the thrust of the piston when the engine is in action. This shape and form also brings the center of gravity low especially when the chamber S. is filled with water.

The casting of the parts together in the form as shown not only saves labor in machine work and assembling but it provides for an equal distribution of the heat by means of the water in chamber S. the heat is conducted from the cylinder V. and the exhaust chest E. to the walls of the column B. which is provided with an unusual large amount of radiating surface and the expansion of the metal as a whole is more even than if it were built up of jointed parts.

The chamber S. holds the water for cooling without any outside connected source of supply, but the cooling effect may be increased when required in the larger or multiple types of engines by inserting in the base portion A. tubular members y. which extend through the water space S. and add to the conduction of the heat from the water.

C. is the top or cover portion of the engine, X. X. are the caps for the crank shaft bearings, Y. Y. are the caps for the cam shaft bearings as shown in Fig. 8. these caps are an integral part of the cover C.

D. is a swinging lid attached or hinged to the cover C.

O. is a shield or splasher fastened to the lid D. and shown in Fig. 4. m. is an oil hole in the cover C. in which a suitable oil cup may be attached. Oil drips from the oil hole m. falling in contact with the connecting rod of the engine; much of this oil is thrown off by centrifugal force to the walls of the cover C. and drains from there down to the cylinder V. some of this oil is thrown against the splasher or shield O. and drips off to the cylinder V. but if the splasher O. were removed the oil would be thrown in contact with the lid D. and much of it would run out between the joint of the lid D. and the cover C. and in order to prevent this the splasher or shield O. is provided. The cover C. also forms the upper half of the housing for the gears d. d. the governor h. and the cams e. e.

Fig. 5. shows a crank shaft I. with geared connection d. d. to the cam shaft N. the cams e. e. the governor h. together with the gears d. d. are located inside of the walls of the column portion B.

On one end of the cam shaft N. is a spark timer L. located outside of the col-

umn walls B. and on the other end of the cam shaft N. and outside of the column walls B. is mounted a pulley J. this pulley travels with the cam shaft N. which is one half of the speed of the crank shaft I. this makes the pulley J. a slow speed pulley 70 as compared with the usual pulley fastened to the fly wheel of the engine. This pulley J. may be used for light work not adapted for the usual fly wheel pulley.

The fly wheel should be located on the 75 crank shaft I. outside of the bearings X. X. in the usual way and need not be shown in the drawing in order to illustrate my invention.

In the larger sizes of engines the column 80 portion B. and the base portion A. together, would be heavy as compared with the usual cylinder of the same size engine. It is often necessary to rebore cylinders when worn, and for these larger sizes of engines I have 85 provided a sleeve or sub-cylinder which fits the inside of the cylinder portion of my invention. The method of fitting this sleeve or sub-cylinder to the cylinder portion is clearly shown in Fig. 9. f. f. is the jointed 90 portion showing the method of fastening together.

While I have shown and described my invention as applied to a single cylinder portion, it is plain that cylinders may be built 95 in multiples and yet the portions shown, cast in one integral whole casting.

What I claim and desire to secure by Letters Patent is:

1. A gas engine comprising an exterior casing the exterior walls whereof are adapted to form a water-chamber, a flange extending from the inner face of said casing, a cylinder pendent from said flange, inlet and outlet ports in the bottom of said cylinder, passage-ways extending from said ports to the walls of said casing, valve compartments extending from said ports and said flange, a crank-shaft and cam-shaft journaled in said casing above said flange, valves operable by said cam-shaft, and means connecting said valves with said cam-shaft through said passage-ways.

2. A gas engine comprising an exterior casing the exterior walls whereof are adapted to form a water-chamber, a flange extending from the inner face of said casing, a cylinder pendent from said flange, inlet and outlet ports in the bottom of said cylinder, passage-ways extending from said ports to the walls of said casing, valve compartments extending from said ports and said flange, the walls of said casing, cylinder and ports being integral, a crank-shaft and cam-shaft journaled in said casing above said flange, valves operable by said cam-shaft, and means connecting said valves with said cam-shaft through said passage-ways.

3. In a gas engine, a hollow body open at the top, a cylinder, an inlet chest, an exhaust chest, all cast in one integral whole, a crank shaft and a cam shaft mounted on the upper edge of said body and above the cylinder, a cover for said body adapted to hold the crank and cam shaft in place, said cover having an opening therein, a lid covering said opening, said lid when closed forming a part of the cover, and a shield or splasher attached to said lid.

4. In a gas engine, a hollow body adapted to form a water chamber, a cylinder, an inlet chest, an exhaust chest, all cast in one piece, a crank shaft and a cam shaft having bearings on said body above the cylinder, a cover for said body, geared connec-

tion between the crank shaft and the cam shaft and a pulley on said cam shaft outside of the said body and cover.

5. In a gas engine, a hollow body adapted to form an open water chamber, a cylinder, an inlet chest, an exhaust chest, all cast in one integral whole, a crank shaft and a cam shaft mounted on said base and operatively connected, a cover on said body adapted to form a housing for the shafts and the gears connecting said shafts, and a driving pulley mounted on said cam shaft.
